Primary Examiner — Patricia A Palasik(74) *Attorney, Agent, or Firm* — Dykema Gossett PLLC(57) **CLAIM**

The ornamental design of a linear actuator, as shown and described.

DESCRIPTION

FIG. 1 is a first perspective view of a first embodiment of a linear actuator showing my new and ornamental design, FIG. 2 is a second perspective view thereof, FIG. 3 is a top plan view thereof, FIG. 4 is a bottom plan view thereof, FIG. 5 is a first side view thereof, FIG. 6 is an opposite, second side view thereof, FIG. 7 is a front end view thereof; and, FIG. 8 is a rear end view thereof.
